(57) **CLAIM**

The ornamental design for a bus, toy replica, and/or other replica, as shown and described.

DESCRIPTION

This application contains subject matter related to the following co-pending U.S. design patent application:

Application Ser. No. 29/806,502, filed herewith and entitled "Bus, Toy Replica, and/or Other Replica".

FIG. 1 is a front elevation view of a bus, toy replica, and/or other replica embodying our new design;

FIG. 2 is a front and left side perspective view thereof;

FIG. 3 is a left side elevation view thereof;

FIG. 4 is a right side elevation view thereof;

FIG. 5 is a rear elevation view thereof;

FIG. 6 is a rear and right side perspective view thereof;

FIG. 7 is a top plan view thereof;

FIG. 8 is a partial and enlarged front elevation view thereof for area 8 in FIG. 1;

FIG. 9 is a partial and enlarged front perspective view thereof for area 9 in FIG. 2;

FIG. 10 is a partial and enlarged left side elevation view thereof for area 10 in FIG. 3;

FIG. 11 is a partial and enlarged left side elevation view thereof for area 11 in FIG. 3;

FIG. 12 is a partial and enlarged rear elevation view thereof for area 12 in FIG. 5;

FIG. 13 is a partial and enlarged rear perspective view thereof for area 13 in FIG. 6;

FIG. 14 is a partial and enlarged rear perspective view thereof for area 14 in FIG. 6;

FIG. 15 is a partial and enlarged top plan view thereof for area 15 in FIG. 7; and,

FIG. 16 is a partial and enlarged top plan view thereof for area 16 in FIG. 7.

The broken lines in the drawings illustrate portions of the bus, toy replica, and/or other replica that form no part of the claimed design.
